UNITED STATES PATENT OFFICE.

HUBERT M. PERRY, OF CHICAGO, ILLINOIS, ASSIGNOR TO ALBERT G. WELCH, TRUSTEE
UNDER THE WILL OF EDWIN S. WOODS, DECEASED.

SIDE BEARING.

1,275,732.

Specification of Letters Patent. Patented Aug. 13, 1918.

Application filed October 22, 1917. Serial No. 197,759.

To all whom it may concern:

Be it known that I, HUBERT M. PERRY, a citizen of the United States, and a resident of Chicago, in the county of Cook and State 5 of Illinois, have invented certain new and useful Improvements in Side Bearings; and I do hereby declare that the following is a full, clear, and exact description thereof, reference being had to the accompanying 10 drawings, and to the letters of reference marked thereon, which form a part of this specification.

This invention relates to improvements in antifriction bearings designed to transmit 15 load between two parts capable of limited relative, oscillating movement, and is shown herein as applied to a side bearing for railroad cars and more particularly to a side bearing to be attached to the truck bolster 20 as distinguished from one carried by the body bolster. The invention consists of the matters hereinafter described and more particularly pointed out in the appended claims.

In the drawings:

25 Fig. 1 is a view representing the bearing in side elevation with a part of the casing wall of the bearing broken away to show the interior construction.

30 Fig. 2 is a top plan view of the bearing with a part of the upright casing wall shown in transverse section.

35 Fig. 3 is a view representing a section through the bearing in a plane indicated by the line 3—3 of Fig. 1.

40 Fig. 4 is a view representing a longitudinal, central section through the bearing.

45 Fig. 5 is a view representing a vertical section through the bearing in a plane indicated by the line 5—5 of Fig. 1.

50 Fig. 6 is a view illustrating the antifriction element of the bearing.

Referring now to that embodiment of my invention illustrated in the accompanying drawings:—10 indicates a casing which contains the antifriction bearing element. It is provided at its base with laterally disposed ears 11 for attaching it to the top of the truck bolster which is indicated by the line 12.

55 The casing 10 consists of a shell, open top and bottom, and having upright side walls 13, 13 and upright end walls 14, 14. The end walls 14, 14 are provided at their bottom ends with inwardly extending, upwardly inclined flanges or extensions 15, 15 which are cored to provide at each end of the

casing, longitudinally spaced, transverse, depending ribs 16, 17.

The bottom edges of the side walls 13, 13 and the depending ribs 16, 16 define a rectangular opening in which is fixed a bottom 60 plate 18, and preferably above this, a wear plate 19. Said plates are held in place, the one upon the other, by means of inwardly projecting lugs 20, 20 on the side walls of the casing (there being four of said 65 lugs located substantially at the four corners of said plates) which engage the top face of the wear plate, and by bending in the bottom ends of the flanges 16, as clearly shown in Fig. 4. The flanges 16 are made 70 parallel to the end walls of the casing in the first instance, but when the device is assembled and after the bottom plate and its wear plate have been placed between and have been brought up against the lugs 20, 75 said flanges are bent under to retain the plates locked in this position.

21 indicates an antifriction roller which is located within the casing and which is adapted to roll longitudinally therein on the 80 wear plate 19, in a familiar manner. Said antifriction roller is provided with overbalance members 22 at its ends which are placed in such manner as to cause the roller to return to a pre-determined, central position within the casing. The overbalance members, as shown, are in the form of end extensions of the main body of the roller. Said extensions are elliptical in cross section and are placed with their greatest focal diameter at right angles to the diameter 21^a of the roller which is intended to be erect or in a vertical position when the roller is centered.

To increase the overbalancing of the roller, 95 it is preferably cored at its ends to produce openings 23 above the overbalance members 22 and above the center of the roller. Said openings are preferably elongated and extend equally to either side of 100 the roller diameter 21^a, which is intended to be perpendicular when the roller is at its central or pre-determined position.

Trunnions 24 are formed on the overbalance extensions 22, with their central axes 105 located in the plane of the aforesaid roller diameter 21^a. In order to guide the roller and also to lock it within the casing, I provide grooves 25 in each side wall of the casing, said grooves being adapted to re- 110

ceive and guide the trunnions 24. Each groove has divergent branches 25^a, 25^a, one being inclined from the middle upwardly toward one end of the casing and the other 5 being likewise inclined toward the opposite end of the casing. Said grooves have a third vertical branch 25^b which opens through the bottom of the casing and is adapted to guide the trunnions of the roller into the casing 10 when the device is assembled.

Curved ribs 26 are provided at the four corners of the casing to be engaged by and to resist the further movement of the roller when it has reached the end of the casing.

15 Said ribs are formed in an arc corresponding to the curvature of the roller.

Suitable ventilation openings 28 are provided at the end walls of the casing near their bottom. Similar ventilation openings 20 25^c are provided in the side walls of the casing in line with the branches 25^b of the grooves 25.

The operation of the device will be apparent from the description thus far given. 25 When not under load, the roller will naturally assume a central or other pre-determined position, as illustrated in Fig. 1.

When the roller is engaged by the bearing plate (not shown) on the body bolster, 30 and is caused to roll toward one end of the casing, it will move to another position, for example, that shown in Fig. 4, the trunnions 24 by their engagement in the branches of the grooves 25, guiding it in this movement 35 and retaining the roller with its axis at right angles to the longitudinal axis of the casing. When the roller is released by the upper bearing plate, the overbalance extensions 22 will cause it to roll back to a central position which it will assume and will approximately retain until it is again engaged and rolled either in one direction or the other.

One of the primary advantages of the construction described, is that no means causing a lift of the body bolster as the roller is rolled toward one or the other end of the casing, is required in order to bring the roller back to central position.

50 By reason of the engagement of the roller trunnions 24 in the divergent branches 25^a of the grooves 25, the roller is prevented from being pushed in a sliding manner, as under a sudden jar, from any position it 55 may have assumed in the casing. This is important, since without some means to prevent such operation of the roller, it might be left at a place other than the pre-determined central position, when released from load, so that it would fail to operate in the way in which it is intended.

I claim as my invention:

1. In an antifriction bearing comprising a casing with upright side and end walls, a 65 horizontal bearing plate adapted to be ap-

plied through the bottom of said casing, a roller longitudinally movable in said casing and mounted on said bearing plate, said roller being provided with an overbalance adapted to return it to a predetermined position within said casing and with eccentrically placed trunnions, and the side walls of said casing having grooves for engagement with said trunnions, said grooves having upwardly inclined, divergent branches adapted to coact with said trunnions, and with a downwardly extending branch opening through the bottom edges of the side walls of said casing.

2. In a side bearing, a casing, a horizontal bearing plate located within said casing, a roller mounted on said bearing plate and movable within said casing, said roller being provided at its ends with overbalance extensions adapted to return it to a predetermined position within said casing under release from load, said roller and casing being provided with inter-engaging parts adapted to lock the roller within the casing and to guide it in its path of travel without interfering with its freedom of movement, and means for maintaining said roller with its axis at right angles to its path of travel.

3. In a side bearing, a casing having upright side and end walls, said casing being open at the top, means providing a bearing plate in the bottom of said casing, and a roller mounted on said bearing plate and movable in the direction of the length of said casing, said roller being provided with overbalance extensions at its ends.

4. In a side bearing, a casing having upright side and end walls, said casing being open at the top, means providing a bearing plate in the bottom of said casing, a roller mounted on said bearing plate and movable in the direction of the length of said casing, said roller being provided with overbalance extensions at its ends, said roller also having trunnions projecting beyond said extensions, and the side walls of said casing having grooves adapted to guide said trunnions when said roller is moved in either direction in said casing in order to maintain said roller with its axis at right angles to its path of travel.

5. In a side bearing, a casing having upright side and end walls and being open at the top and bottom, means providing a horizontal bearing plate within and closing the open bottom of said casing, a roller mounted on said bearing plate and movable in the direction of the length of said casing, said roller being inserted into said casing through said open bottom and having overbalance extensions at its ends, trunnions projecting beyond said extensions, the side walls of the casing each having diverging grooves adapted to guide said trunnions in the movement

of said roller in said casing, said diverging grooves in each side wall, merging into a single upright groove which extends downwardly to the bottom edge of its respective side wall.

6. In a side bearing, a casing having upright side and end walls and being open at the top and bottom, means providing a horizontal bearing plate within and closing the open bottom of said casing, a roller mounted on said bearing plate and movable in the direction of the length of said casing, said roller being inserted into said casing through said open bottom and having overbalance ²⁰ tensions at its ends, trunnions projecting beyond said extensions, the side walls of the casing each having diverging grooves adapt-

ed to guide said trunnions in the movement of said roller in said casing, said diverging grooves in each side wall merging into a single upright groove which extends downwardly to the bottom edge of its respective side wall, the said end walls having ribs adapted to limit the movement of the roller upon said horizontal bearing plate. ²⁵

In testimony that I claim the foregoing as my invention I affix my signature in the presence of two witnesses, this 16th day of October, A. D. 1917.
